United States Patent Office

Des. 226,893
Patented May 15, 1973

226,893

DEAD LOCK LEVER

Raymond U. H. Tegner, Rockford, Ill., assignor to
Amerock Corporation, Rockford, Ill.

Filed Jan. 10, 1972, Ser. No. 216,905

Term of patent 14 years

Int. Cl. D8—07

U.S. Cl. D8—137

FIG. 1.

FIG. 2.

FIG. 3.

FIG. 4.

FIG. 5.

FIG. 1 is a front view of a dead lock lever incorporating my new design.

FIG. 2 is a side view of the lever.

FIG. 3 is an end view as seen from the left in FIG. 2.

FIG. 4 is an enlarged sectional view taken along the line 4—4 in FIG. 1.

FIG. 5 is an enlarged sectional view taken along the line 5—5 in FIG. 1.

I claim:

The ornamental design for a dead lock lever, as shown.
